HUMIDIFIER RESERVOIR

Burton Shaffer, Lincoln Wood, and Philip J. Burnstein,
Skokie, Ill., assignors to Hamilton Humidity, Inc., Chi-
cago, Ill., a corporation of Illinois

Filed Oct. 11, 1968, Ser. No. 13,946

Term of patent 14 years

Int. Cl. D23—04

U.S. Cl. D23—146

Fig. 3

Fig. 3

FIGURE 1 is a front perspective view of the humidifier reservoir design in accordance with this invention, showing the ornamental general shape of the reservoir when viewed from above;

FIGURE 2 is a rear perspective view of the reservoir design of FIGURE 1, showing the ornamental general shape of the reservoir when viewed from below;

FIGURE 3 is a top plan view of the reservoir, as viewed along the line 3—3 in FIGURE 1;

FIGURE 4 is a bottom plan view of the reservoir, as viewed along the line 4—4 in FIGURE 1;

FIGURE 5 is an elevational front end view of the reservoir, as viewed along the line 5—5 in FIGURE 3;

FIGURE 6 is an elevational side view of the reservoir, as viewed along the line 6—6 in FIGURE 3;

FIGURE 7 is an elevational rear end view of the reservoir, as viewed along the line 7—7 in FIGURE 6; and

FIGURE 8 is an elevational cross-sectional view of the reservoir, taken along the line 8—8 in FIGURE 6.

The dominant features of our design reside in the portions shown in full lines.

We claim:

The ornamental design for a humidifier reservoir, substantially as shown and described.
